UNITED STATES PATENT OFFICE

101,147

DESIGN FOR AN AIR MOISTENER

Alex Sternberg, Chicago, Ill., assignor to Interstate Metal Products Co., Chicago, Ill., a corporation of Illinois

Application July 13, 1936, Serial No. 63,818

Term of patent 14 years

To all whom it may concern:

Be it known that I, Alex Sternberg, a citizen of the United States, and residing at Chicago, county of Cook, and State of Illinois, have invented a new, original, and ornamental Design for an Air Moistener, of which the following is a specification, reference being had to the accompanying drawing forming a part thereof.

Figure 1 is a front view of the air moistener, showing my new design;

Figure 2 is a side view thereof;
Figure 3 is a top plan view, and
Figure 4 is a back view.

I claim:

The ornamental design for an air moistener as shown.

In witness whereof I affix my signature:

ALEX STERNBERG.
